UNITED STATES PATENT OFFICE.

SWEN JOHNSON, OF HURON, AND JOHN JOHNSON, OF ARLINGTON, SOUTH DAKOTA.

LUBRICATOR.

1,180,588.

Specification of Letters Patent. Patented Apr. 25, 1916.

Application filed March 13, 1915. Serial No. 14,151.

To all whom it may concern:

Be it known that we, SWEN JOHNSON and JOHN JOHNSON, citizens of the United States of America, residing, respectively, at 5 Huron, county of Beadle, State of South Dakota, and Arlington, in the county of Kingsbury and State of South Dakota, have invented certain new and useful Improvements in Lubricators, of which the following is a specification.

The present invention relates to improvements in lubricators, and is especially designed to provide a system of control and automatic feed for lubricators, as applied to 15 locomotive engines.

The primary object of the invention is to utilize in connection with the automatic feed to the cylinders of the engine, a supplemental manually operated means by 20 which the automatic feed regulator may be used when the locomotive is not working, but is drifting or coasting, in order that oil may be fed to the cylinders as usual.

The invention consists in certain novel 25 combinations and arrangements of parts as will be hereinafter more fully pointed out and claimed.

In the accompanying drawings we have illustrated one complete example of the 30 physical embodiment of our invention, constructed according to the best mode we have so far devised for the practical application of the principles of the invention.

Figure 1 is a view in elevation, showing 35 the oil chamber and its attachments involving our invention. Fig. 2 is a longitudinal vertical sectional view of the upper portion of the wall of the oil chamber showing the channels and passages from the oil chamber. 40 Fig. 3 is an enlarged transverse sectional view of the oil chamber showing one of the connections for oil to the cylinders. Fig. 4 is a sectional view showing the automatic control device and its manually operative 45 connections. Fig. 5 is an outside view of the cylinder of the control device. Fig. 6 is a view showing the operating lever. Fig. 7 is an edge view of the lever. Fig. 8 is an end view of the cylinder of the automatic feed control. Fig. 9 is a sectional view showing the feed control device. Fig. 10 is a sectional view showing the automatic feed 50 control to the air pump.

In the preferred embodiment of our in-

vention we employ the oil chamber 1, which 55 is attached by means of the bracket 2 to the boiler head, and a drain 3 and inlet or filling opening 4 are provided for the oil chamber as usual.

In the upper wall of the cylinder which 60 forms the oil chamber, we have illustrated connections as A, B, and C, which are adapted to supply oil to the air pump and to the two main cylinders, respectively 65 through the pipes A', B', and C'. The bull's eye chambers 5, 6 and 7, which form the connection between the feed to the air pump and cylinders, and the oil chamber, are in communication with the interior of the oil chamber, as shown in Fig. 2. The 70 chamber 5 is connected with the oil chamber through the vertical passage 8 and the enlarged port 9 between which is located a seat 10. This seat and opening are adapted to be governed by means of the automatically operated valve stem 11 of the piston 12, which is attached to the diaphragm 13, and movable in the chamber 14 of the automatic steam feeding device for the air pump. The steam is admitted to the chamber 15 of this device through pipe 16 and outlet 17, and the pressure of steam, as will be readily understood, moves the piston 12 against spring 18 to open or close the valve seat 10, as the steam pressure varies as usual. 80 The usual condensing chamber 19 is connected to the oil chamber, and steam for the chamber is conducted thereto through the pipe 20.

The feed of lubricant to the two engine 90 cylinders is governed and regulated by the automatic control device at the opposite end of the cylinder 1. This device is attached to the threaded boss 21 by means of the coupling 22. This coupling has a passage 95 therethrough for the piston stem 23 which is movable in the channel 24, extending through the upper wall of the valve chamber, and this channel 24 is connected by vertical passages 25 and 26, to the respective 100 chambers 6 and 7. Seats 27 and 28 are provided in the channel 24 for a needle valve as 29 by which the flow of oil through the respective vertical passages 25 and 26 may be permanently fixed. In Fig. 3, one of 105 these needle valves is shown connected through the boss 30 and gland 31, and provided with a head 32 for turning the stem.

These needle valves regulate the permanent flow of oil to the main cylinders. The channel 24 communicates with the interior of the oil chamber through a port 33, and it will readily be understood that the oil flows through the port 33, channel 24, and the passages 25 and 26 to the respective cylinders when the engine or locomotive is working. A valve seat 34 is provided in the channel 24 for the piston stem 23, and this piston stem or valve stem governs the passage of oil through the opening or seat 34. It will be understood that the supply to the cylinders is cut off when the engine is not working by the needle valves 23, and the automatic control device is adapted to both automatically and manually control the feed of oil through the valve seat 34.

The valve stem 23 is formed with a piston 35 movable in the cylinder 36 of the control device. This cylinder is threaded on to the coupling 22, as shown in Fig. 9, and the cylinder receives steam through the openings 36' and 37, which are connected by pipes to the source of supply. The piston 35 is movable in the cylinder 36 against the pressure of a spring 37, and in this manner the flow of oil through the valve seat 34 is regulated by the steam pressure passing through the ports 38—38 into the cylinder 36, and moving the valve stem by pressure on the piston 35, as understood. The piston 35 is formed with an extension or post 39, and around this post is located a bushing 40 having an enlarged end or head 41 seated in the annular recess 42 of the piston. In Fig. 4, it will readily be seen that the spring 37 has one end 43 secured in a cavity or recess in the head 41, and its other end 44 is secured in a cavity or recess in the reduced end of the cylinder 36.

At the end of the cylinder an operating lever 45 is attached. This lever has an open round head 46 and fits over the end of the bushing 40, and is secured thereto by means of a key 47. The head 46 of the lever has a cam face or projection 48 which is adapted to engage with either the two recesses 49 or 50 on the end of the boss 51 integral with the cylinder 36. By means of a washer 52 and a key 53 which secures the washer to the post 39, the lever 45 is secured on the bushing and post against removal, but it will be understood that the lever 45 may be oscillated on the post through the bushing 40. Thus, in addition to the regulation of the flow of oil through the seat 34 by the pressure, the oil feed may be regulated by movement of this lever 45. For instance, with the projection 48 in the recess 50, the oil is permitted to pass through the seat 34.

When a locomotive is making an extended coast, or drifting, after the steam has been shut off, and it becomes necessary to feed oil to the cylinders, the lever 45 may be turned

so that the projection 48 is removed from the recess 49 and permitted to rest in the recess 50. In Fig. 5, it will be seen that the recess 49 is deeper than the recess 50, and therefore the valve stem 23 is withdrawn from the seat 34, and the flow of oil is permitted through this seat to the cylinders. The lever is held in this position by the cam projection 53 which prevents movement of the projection 48 from the recess 50. When the steam is again applied and the piston 35 is moved back by the steam pressure against the coil spring 37, the head 46 of the lever is freed from the boss 51, and the torsional strength of the spring 37 is exerted to swing the lever 45 back to its original position, and the automatic action of the feeding device is again operative. In this manner the lubricating stem may be controlled both automatically and manually, and the piston feed device of the combined automatic and manual control permits oil to flow to the engine when it is working under usual conditions and automatically, but in addition permits the flow of oil, when the lever is properly actuated, to the cylinders, although the engine may not be working. It will be understood, of course, that the chambers 5, 6 and 7 are closed with the proper devices and contain the water, as usual, through which the oil flows and the oil is conducted by the suitable pipes to the air pump and to the two main cylinders of the engine.

From the above description taken in connection with our drawings, it is evident that we have provided a system of lubrication for locomotive engines which is facile, economical, and efficient in operation, both under the usual automatic conditions, and under the manual control, and the device is of great value in that it provides means by which the engineer may feel assured at all times that proper lubrication of the parts is going on.

What we claim is:

1. The combination in a lubricating system including an oil chamber and an oil channel, and connections with the main cylinders of an engine, of a valve stem, a cylinder and a piston on the stem manually operable for permitting flow of oil during the absence of steam pressure, and said cylinder and piston co-acting with the stem when actuated by steam pressure for automatically permitting control of the oil valve by steam pressure.

2. A fluid pressure operated control device comprising a valve stem, a cylinder and a piston on the stem movable in the cylinder, a post forming an extension of the stem, a bushing on the post and a spring surrounding said bushing and located between a portion of the cylinder and said piston, and said cylinder having an inlet for steam pressure at the side of the piston opposite the spring.

3. A lubricator feed regulating device comprising a cylinder with a piston and valve stem therein and a post forming an extension of the valve stem, a bushing on 5 said post, an operating lever fixed to the bushing, means for adjusting said lever relative to the cylinder, and means within the cylinder for holding the lever in normal position.

In testimony whereof we affix our signatures in presence of two witnesses.

SWEN JOHNSON.
JOHN JOHNSON.
